UNITED STATES PATENT OFFICE.

CHARLES W. LOGAN, OF KENMORE, NEW YORK.

DESIGN FOR A CHANDELIER.

Application filed March 10, 1928 Serial No. 25,789. Term of patent 3½ years.

To all whom it may concern:

Be it known that I, CHARLES W. LOGAN, a citizen of the United States, residing at Kenmore, in the county of Erie, and State of New York, have invented a new, original, and ornamental Design for a Chandelier, of which the following is a specification, reference being had to the accompanying drawing, forming part thereof.

In said drawing: The figure is an elevation of a chandelier embodying my new design.

I claim:

The ornamental design for a chandelier, as shown.

CHARLES W. LOGAN.
